(57) **CLAIM**

I claim the ornamental design for a lifting grip, as shown and described.

DESCRIPTION

Preferably the lifting grip is used for lifting bulky materials, boxes and cartons.

FIG. 1 is a lower left front perspective view of a lifting grip;

FIG. 2 is an upper right rear perspective view of the lifting grip;

FIG. 3 is a front elevational view thereof;

FIG. 4 is a right side elevational view of the lifting grip the left side being a mirrorimage thereof;

FIG. 5 is a rear elevational view thereof;

FIG. 6 is a top plan view thereof; and,

FIG. 7 is a bottom plan view thereof with the unclaimed portion removed.

The broken lines are for environmental purposes only and merely represent an array of projections attached to a fastening portion to which the lifting grip, having the design shown and described, is attached and form no part of the claimed design.
